ELMER E. HENDERSHOT AND EDWARD J. MARSHALL, OF ROCKAWAY, NEW JERSEY.

INSECT-CATCHING DEVICE OR TRAP.

1,279,865.

Specification of Letters Patent. Patented Sept. 24, 1918.

Application filed July 19, 1916. Serial No. 110,092.

To all whom it may concern:

Be it known that we, ELMER E. HENDERSHOT and EDWARD J. MARSHALL, citizens of the United States, residing at Rockaway, 5 county of Morris, State of New Jersey, have invented a new and useful Insect-Catching Device or Trap, of which the following is a specification.

Our invention relates to improvements in 10 said insect traps, and more especially to that class of traps adapted for catching insects, or bugs which may frequent furniture, beds, etc., and the objects of our invention are—

15 1. To provide a device of the character described which may be easily adjusted to, or upon a bedstead.

20 2. Such a device constructed in a simple, cheap, and efficient form.

25 3. Such a device as may be instantly and readily removed from, or applied to the furniture in question as may be desired.

With these and other objects in view, attention is called to the accompanying drawings, explanatory of the specification, and 25 wherein—

Figure I is an elevation of one leg of the bedstead, showing the apparatus in place.

Fig. II is a transverse sectional view.

Fig. III is a vertical sectional view.

30 Fig. IV is a detail view, showing the arrangements of the parts.

Similar figures refer to similar parts throughout the several parts.

Referring more particularly to the drawings, 1 represents the case or receptacle as a whole, which may be constructed of any suitable material, and in any desired form as circular, oval, or square. The case 1 is composed of a bottom plate 2, and an up-

wardly projecting rim 3. Through the center of the bottom plate 2 is pierced a hole 4 to permit the passage of the shank of the caster. The bottom plate 2 at the upper side thereof, and at its central portion is thick-

45 ened to form a boss as shown at 8, so that when the leg of the bedstead is set within the case, a certain space 5 may be left between the bottom surface of the leg, and the interior face of the case. The purpose of

50 this arrangement is to leave a sufficient space 5 to receive the semi-circular gummed washers 6, and so that said semi-circular washers may be easily inserted, or removed from the case, and may be easily adjusted up under

the leg, or removed as desired. Such insertion, or removal is facilitated by means of the ears 7 attached to the outer edge of the washers 6. The upper surfaces of said semi-circular washers 6 are treated with a composition composed of one part castor-oil to 55 three parts rosin melted together, said compositions forming a viscous and sticky substance designed to catch and hold any insect which may come into contact therewith.

It will be noted that the two semi-circular 60 washers 6, when joined, form a perfect whole. It will also be noted that the elements of this invention may be changed as respects form and material so as best to adapt the device to the purposes intended. 70 It will also be noted that this device constitutes an efficient fly trap when used separate and apart for that purpose, and that for this purpose it may be placed upon windowsills, tables, or elsewhere as desired. 75

In actual use upon a bedstead, the preferable location is between the bottom of the leg and the caster, the caster shank being thrust through hole 4 up into the leg whereby the device is held in firm position, or if 80 this arrangement is for any reason impracticable, the entire case may be set upon the floor and the caster or base of the leg may be set within the case.

It will be seen that with the device so 85 placed, and with the washers 6 in position, said washers being treated with the composition as aforesaid, or other similar compositions, an effective barrier is offered against insects, or bugs attempting to cross over said 90 washers so as to climb up the legs of the furniture.

While we have herein described certain specific manner and method of constructing our said invention, it is understood that we 95 may vary from the same in minor details, not departing from the spirit of the invention so as best to construct the invention to meet the particular requirements.

Having so described our invention, what 100 we claim to be new and patentable is:

1. An insect trap comprising a case, an apertured boss carried by the bottom thereof, semicircular washers surrounding said boss to afford a gummed surface between the 105 sides of said case and boss and ears carried by said washers and projecting beyond the sides of said case.

2. An insect trap comprising a receptacle open at the top and adapted to be placed beneath the leg of a piece of furniture and a sectional member having a central opening 5 so as to surround the said leg and provided with a gummed upper surface, said member being divided into removable sections to enable it to be placed in and removed from

the receptacle without removing the latter from the said leg.

ELMER E. HENDERSHOT.
EDWARD J. MARSHALL.
